UNITED STATES PATENT OFFICE.

PETRUS J. FRANÇOIS, OF QUEBEC, QUEBEC, CANADA.

PROJECTILE.

1,303,877.

Specification of Letters Patent. Patented May 20, 1919.

Application filed July 1, 1918. Serial No. 107,062.

To all whom it may concern:

Be it known that I, PETRUS J. FRANÇOIS, a citizen of the United States, residing at Quebec, in the Province of Quebec and Dominion of Canada, have invented certain new and useful Improvements in Projectiles; and I do hereby declare the following to be a full, clear, and exact description of the invention, such as will enable others skilled in the art 10 to which it appertains to make and use the same.

This invention has for its object to provide an improved type of projectile carrying a plurality of variously directed cartridges 15 or bullets which are discharged during the flight of the projectile at right angles to the course of the latter.

Another object is the provision of means for automatically and intermittently firing 20 the cartridges or bullets from the projectile during the flight of the latter, and means operable by the impact of the projectile against the target or other object for firing all of the cartridges or bullets carried by the 25 projectile.

With these and other objects in view, the invention consists in the novel construction, combination and arrangement of parts as will be hereinafter specifically described, 30 claimed and illustrated in the accompanying drawings, in which:

Figure 1 represents a longitudinal sectional view through the improved projectile,

Fig. 2 represents a transverse sectional view on the line 2—2 of Fig. 1,

Fig. 3 represents a fragmentary side elevation of the tube removed from the projectile,

Fig. 4 represents a transverse sectional view on the line 4—4 of Fig. 1.

Referring to the drawings in detail, wherein similar reference numerals designate corresponding parts throughout the several views, the numeral 5 indicates the body of 45 the projectile which is preferably divided transversely and longitudinally to provide a plurality of sections, which may be quickly and conveniently assembled and which permits of the bullets or cartridges being inserted in position therein. The forward extremity of the projectile body is tapered, or pointed, as indicated at 6, and the rear end thereof is formed with a chamber 7 receiving a charge of explosive material 8, which is 50 adapted to be ignited when the projectile is

fired by a cannon or other gun, the fire of the gun penetrating an opening 9 formed in the rear extremity of the body. A plurality of blades 10 are pivotally secured at 11 in recesses 12 formed longitudinally of the body 60 5 and are adapted, when the projectile leaves the gun, to be thrown outwardly to operative position by the tension of the springs 13 to guide the projectile in its flight.

The body 5 is formed with a longitudinal bore 14, which communicates at its rear end by a restricted passage 15 with the chamber 7 and is reduced adjacent its rear end and internally screw threaded, as at 16, to receive the tube 17, which is arranged in spaced 70 relation to the wall of the bore 14 and is formed with a plurality of longitudinal slots 18.

The projectile body 5 is formed with a plurality of annular series of radial openings 20, receiving bullet-carrying cartridges 21. Each of the several cartridges 21 is adapted to be fired by the outward movement of a firing pin 22 associated therewith, which is mounted in a guide or block 23 rigidly 80 secured in the wall of the bore 14. The cartridges of each group are fired by an annular member 24 slidably mounted within the tube 17 and carrying a plurality of radially projecting lugs 25 having beveled outer edges 85 adapted, during rearward movement of the ring, to engage and move the firing pins 22 outwardly into engagement with the percussion caps of the cartridges 21. A pair of levers 27 is pivotally secured to each ring 24 90 within the tube 17.

Each ring 24 is arranged forwardly of a block of relatively hard explosive material 28, which is arranged in the tube 17 and is engaged by the rear extremities of the levers 95 27. The ring is automatically moved rearwardly within the tube, subsequent to the consumption of the explosive material 28, by the tension of a spring 30, which is coiled about the tube 17 and confined between outwardly projecting lugs 31 formed upon said tube and the radially projecting lugs 25 of the ring 24. The rearmost block of explosive material 28 is supported upon the explosive charge 8, and the blocks arranged forwardly thereof are supported upon inwardly projecting lugs 32 formed interiorly of the tube 17.

A plurality of longitudinally movable rods 33 are slidably engaged in the outer surface 110

of the tube 17 and are formed with longitudinal slots 34, slidably receiving the radially projecting lugs 25 of the rings 24. The rods are normally retained in forwardly 5 extended position by the tension of a coil spring 33^a. The rear surfaces of the rods 33 are formed with ribs 35, which extend along the edges of the slots 34 and are slidably received within the slots 18 of the tube 17, whereby the longitudinal movement of the rods with relation to the tube is guided. The several rods 33 are formed with a plurality of pairs of beveled lugs 36, which are arranged forwardly of the several firing 10 pins 22 and are adapted to engage and move the latter outwardly when the rods 33 are moved rearwardly within the casing.

A plunger 38 is slidably mounted in an opening formed in the forward extremity 20 of the projectile body 5, projects a distance forwardly of the latter and is engaged at its rear end with a plate 39, which latter is slidably mounted in the tube 17 and is provided with a plurality of radially projecting arms 40 extending through the slots 18 in the tube and engaging the upper extremities of the several rods 33. When the projectile is fired from a gun, the explosive material in the chamber 7 is ignited and as 25 the rearmost block of relatively hard explosive material 28 is burned the ring 24 is released and moves rearwardly under the tension of the spring 30, engaging the beveled surfaces of the lugs 25 with the pin 22, moving the latter outwardly and thus firing 30 the several cartridges 21 in the rear group. Subsequent to the release of the first ring 24, the block 28 of explosive material supporting the second ring is burned, thus 35 releasing the second ring and permitting it to move rearwardly under the tension of its actuating spring 30, and thus firing the second group of cartridges 21. This operation is repeated until all of the blocks 28 have 40 been burned and all of the cartridges 21 have been fired. Should the projectile strike the target or other object before all of the cartridges 21 have been fired, the plunger 38 is moved rearwardly by the impact of 45 the projectile against the object, thus moving the plate 39 and rods 33 rearwardly against the tension of the spring 33^a and engaging the lugs 36 of the rods with the firing pins 22 and firing all of the cartridges 50 carried by the projectile. As suggested in Fig. 3 the several lugs 25 carried by each ring 24 are preferably arranged in staggered or offset relation, so as to intermittently fire the cartridges of the group 55 during the rearward movement of the ring under the influence of its actuating spring 30.

The forward extremity of the projectile body is formed with an internal chamber 42 60 receiving a charge of explosive material 43

which is ignited by a percussion cap 44, subsequent to discharge of the several cartridges 21, and completely destroys the projectile. The percussion cap is provided with a plunger 45 adapted to be moved outwardly by a beveled lug 46 carried by a plate 47, which latter is movably mounted in the tube 17 and is normally retained in rearwardly extended position by the tension of a spring 48. The plate 47 is normally supported in inoperative position upon the levers 27 of the front ring 24.

What I claim is:

1. A projectile comprising a body, a plurality of cartridges mounted in said body 80 and adapted to be fired therefrom, means for intermittently firing the cartridges from said body, and means independent of the first-mentioned firing means for simultaneously firing all of the cartridges not previously fired by the intermittent firing means.

2. A projectile comprising a body having substantially radial cartridge-receiving openings therein, a plurality of groups of 90 relatively stationary cartridges arranged in said body and adapted to be fired therefrom, firing pins associated with said cartridges, and means for successively and intermittently actuating the firing pins associated 95 with the groups of cartridges.

3. A projectile comprising a body, a plurality of cartridges arranged in said body and adapted to be fired therefrom, means for intermittently firing said cartridges 100 from said body, and combustible means normally holding the firing means against operation.

4. A projectile comprising a body, a plurality of cartridges arranged in said body 105 and adapted to be fired therefrom at an angle to the path of the projectile, mechanically operated means for intermittently firing said cartridges, and combustible means normally holding the firing means against 110 operation.

5. A projectile comprising a body, a plurality of cartridges arranged in said body, means for intermittently firing said cartridges, combustible means controlling the 115 operation of the firing means, an explosive charge arranged in the forward portion of said body, and means associated with said firing means for automatically igniting said explosive charge to destroy the projectile 120 body.

6. A projectile comprising a body, a plurality of cartridges arranged in said body and adapted to be fired therefrom, means normally tending to fire said cartridges, and 125 combustible means for controlling the operation of the firing means.

7. A projectile including a body, a plurality of cartridges arranged in said body and adapted to be fired therefrom, means 130

for firing said cartridges, and combustible means for intermittently releasing the firing means.

8. A projectile comprising a body, a plurality of cartridges arranged in said body and adapted to be fired therefrom, said cartridges being arranged in groups in said body, firing means associated with each cartridge group, and combustible means for intermittently releasing the firing means associated with the several groups of cartridges to fire the latter.

9. A projectile comprising a body, a plurality of cartridges arranged therein and adapted to be fired therefrom, mechanically operated means normally tending to fire said cartridges, and combustible means for controlling the operation of the mechanically operated means.

10. A projectile comprising a body, a plurality of cartridges arranged in groups in said body, mechanically operated means as-

sociated with each group of cartridges adapted to fire the latter, and combustible means normally holding the firing means against operation and adapted to intermittently release the firing means associated with the several groups of cartridges.

11. A projectile comprising a body, a plurality of cartridges arranged in said body, mechanically operated means normally tending to fire the cartridges, combustible means normally holding the firing means against operation and adapted to release the firing means, and means associated with the firing means to effect the complete destruction of the body.

In testimony whereof I affix my signature in presence of two witnesses.

PETRUS J. FRANÇOIS.
